(57) **CLAIM**

The ornamental design for an LED lamp, as shown and described.

DESCRIPTION

FIG. 1 is an upper perspective view of a first embodiment of the lamp, the following FIGS. 2-4 also describing the first embodiment;

FIG. 2 is a side elevational view of the lamp, the side elevational view from all sides of the lamp being the same;

FIG. 3 is a bottom view of the lamp;

FIG. 4 is a top plan view of the lamp.

FIG. 5 is an upper perspective view of a second embodiment of the lamp, the following FIGS. 6-8 also describing the second embodiment;

FIG. 6 is a side elevational view of the lamp, the side elevational view from all sides of the lamp being the same;

FIG. 7 is a bottom view of the lamp; and,

FIG. 8 is a top plan view of the lamp.

The broken lines on the drawings depict portions of the lamp that form no part of the claimed design. References to "side", "top", and "bottom" in the figure descriptions are not meant to require certain in-use orientation; a lamp according to the claimed design may be used in any orientation.
